UNITED STATES PATENT OFFICE.

GUY C. HOWARD, OF EVERETT, WASHINGTON

TUBE-MILL.

1,113,120.

Specification of Letters Patent.

Patented Oct. 6, 1914.

Application filed August 28, 1912. Serial No. 717,085.

To all whom it may concern:

Be it known that I, GUY C. HOWARD, a citizen of the United States, residing at Everett, in the county of Snohomish and State of Washington, have invented certain new and useful Improvements in Tube-Mills, of which the following is a specification.

This invention relates to tube mills and more particularly to that class of mills which are employed for disintegrating fibrous material into pulp for paper stock.

The object of the invention is the provision of means whereby the operation of a mill of this type is improved and rendered more efficient for the treatment of various grades or characters of material.

To this end, the invention consists in the novel construction and combination of devices as will be hereinafter described and claimed.

In the accompanying drawings, Figure 1 is a longitudinal vertical section of a portion of a tube mill embodying my invention. Fig. 2 is a side elevation of the mill with the barrel thereof shown partly broken away; and Fig. 3 is a front elevation of the partition screen illustrated in Fig. 1.

The mill may be, as regards its barrel and the manner of mounting the same, of any usual or suitable construction. As illustrated, said barrel is comprised of a cylindrical shell 5 provided with end flanges to which the front and rear heads 6 and 7 are secured. Said heads are respectively provided with axially disposed hollow trunnions 6' and 7' which are journaled in standards 8 and 9 of a supporting frame. Extending into the trunnion 6' is the spout 40 of a feed hopper 10 whereby material to be ground or macerated is supplied to the mill. Adjacent to the rear end of the barrel is an apertured partition or screen 11. Extending rearwardly from this screen is a boss 12, and blades 13 extend radially from the latter into juxtaposition with the inner surface of the head 7. At the outer end of the trunnion 7' is a seat 7" for a valve 14 which, as shown, is mounted upon a tubular stem, or pipe, 15 which serves as a conduit for the passage of water from a chamber 16, provided in an attachment 17 of the machine frame, to a chamber 18 provided in the boss 12. The water is further conveyed by a pipe 19 from the chamber 18 to the space within the shell and is desirably delivered

thereinto in proximity to the midlength of the shell. To afford non-leakable joints where the stem enters such chambers, stuffing boxes 20 and 21 are provided. Intermediate of its length the stem 15 is provided exteriorly with screw threads 15' which engage threads provided within a block 17' depending from the aforesaid attachment 17. A hand wheel 22, or an equivalent, is rigidly secured to the stem 15 to enable the operator to conveniently rotate the latter for advancing or withdrawing the valve 14 with respect to its seat 7" to correspondingly close or open the discharge opening afforded by the hollow trunnion 7'. A lock nut, denoted by 23, may be employed upon said screw threads for the purpose of securing the stem against end play subsequent to the setting of the valve. 24 represents a hopper to receive the output of the mill; and 25 is a pipe provided with a valve 25' for supplying water or chemical solutions to the mill.

In operation, material is fed into one end of the barrel through hopper 10 and after being ground or disintegrated is discharged from the other end through the hollow trunnion 7' into a hopper 24. During such operation a selected quantity of water is supplied through pipe 19 to the interior of the barrel at, or near, the mid length of the same. This water not only contributes to the disintegration of the material, but also serves as a vehicle delivery whereby it is carried from the barrel. The valve 14 is regulated to control or throttle the discharge so that the treatment of the material will endure for a predetermined time with a continuous and regular flow through the mill. Furthermore, the valve controlling the orifice of the barrel discharge is adjustable while the machine is in operation, a function which is peculiarly advantageous with paper-pulp mills.

What I claim is:—

1. In a machine of the class described, the combination with the rotary barrel provided with an axially disposed opening at one end, of a valve non-rotatable with the barrel for regulating the effective area of said opening, and a water supply pipe extending through said valve and communicating with the interior of the barrel intermediate said opening and the opposite end of the barrel.

2. In a machine of the class described, the combination with the rotary barrel provided

with an axially disposed opening at one end, through which the material is discharged from the barrel, of a conical valve for said opening coöperating with a seat provided therefor, and means for regulating the amount of opening of the valve with respect to said seat, said means including a water-supply pipe communicating with the interior of the barrel.

10 3. In a machine of the class described, the combination with the rotatable barrel provided with an axially disposed discharge opening, of a valve for said opening, a water supply pipe extending through the valve and into the barrel, and affording means for controlling said valve to regulate the effective area of said discharge opening.

4. In a machine of the class described, the combination with the barrel and a hollow trunnion therefor, which serves as the discharge opening of the barrel, of a valve movable axially of said trunnion for regulating the effective sizes of said opening, a water supply pipe extending through the valve, and communicative connections between the

pipe and the interior of the barrel, said connections terminating in proximity to the mid length of the latter.

5. In a machine of the class described, the combination with the rotatable barrel provided with an axially disposed discharge opening, a water supply pipe extending through said opening and into said barrel, and a valve for said opening mounted upon said supply pipe and openable outwardly of the opening.

6. In a machine of the class described, the combination with the barrel provided with an axially disposed discharge opening, of a valve openable outwardly in directions parallel to the axis of said opening for regulating the discharge therethrough, and a water-supply pipe supporting the valve and communicating with the interior of the barrel.

Signed at Seattle, this 17th day of August 1912.

GUY C. HOWARD.
